US0D1047297S

(12) **United States Design Patent** (10) **Patent No.:** **US D1,047,297 S**
(45) **Date of Patent:** **** Oct. 15, 2024**

(54) **SUPPLEMENTAL HELMET PROTECTION ATTACHMENT**

(71) Applicant: **VICIS IP, LLC**, New York, NY (US)

(72) Inventors: **Noah Lanphear**, Seattle, WA (US);
Kurt Fischer, New York, NY (US);
Miguel Herrera, New York, NY (US)

(73) Assignee: **VICIS IP, LLC**, New York, NY (US)

(**) Term: **15 Years**

(21) Appl. No.: **29/845,803**

(22) Filed: **Jul. 11, 2022**

Related U.S. Application Data

(62) Division of application No. 29/705,077, filed on Sep. 9, 2019, now Pat. No. Des. 957,741.
